UNITED STATES PATENT OFFICE.

ELSIE LARSON, OF MINNEAPOLIS, MINNESOTA.

BONNET.

Application filed May 29, 1924. Serial No. 716,635.

My invention provides an extremely simple launderable bonnet or cap adapted to be readily made in plain and in different ornamental designs. The bonnet or cap is 5 adapted to be made from a single piece of cloth or from several pieces of cloth stitched together in the form of a sheet adapted to be laid out approximately flat and, hence, to be easily washed and readily ironed. 10 The body of the bonnet or cap, when laid out flat, has four sides and is preferably made more narrow at its rear than at its front edge. On its side edges, it is provided with separable fasteners, preferably 15 buttons and buttonholes, the arrangement being such that the two sides of the piece or sheet are adapted to be gathered in folds and independently held in the gathered condition at the two sides to give form to the 20 bonnet or cap.

As above indicated, the bonnet or cap may be made in various different designs, some of which may be very ornamental.

The invention is illustrated in the accompanying drawings, wherein like characters indicate like parts throughout the several views.

Referring to the drawings:

Fig. 1 is a plan view showing the bonnet or cap-forming sheet laid out flat;

Fig. 2 shows the bonnet or cap partly formed; and

Fig. 3 shows the bonnet or cap completely formed.

In the drawings, a quite plain or simple form is illustrated and, as here illustrated, the four-sided bonnet or cap-forming sheet 1 is provided at its front edge with a brim 2, shown as having a ruffle 5'. At the junction of the body 1 with the brim 2, there is a stitched-on reinforcing band 3 on the ends of which outside buttons $a-a$ are sewed and on the intermediate portion of which, equi-distant from the buttons a , other

buttons $b-b$ are sewed. At the rear corners, the sheet 1 is provided with buttonholes a^1-a^1 , and at its rear sides, it is formed with buttonholes a^2-a^2 and b^1-b^1 . Preferably, the sheet 1, where the buttonholes a^2 and b^1 are worked, is doubled together and the buttonholes are worked through both thicknesses thereof, thereby forming tucks, which, when the sheet is laid out flat for ironing, as shown in Fig. 1, will be ironed down flat.

In giving form to the bonnet or cap, the

rear corners of the sheet 1 are moved up and the buttonholes a^1 are applied on the buttons a , and this causes the sides of the cap to take substantially the form shown in 60 Fig. 2, by reference to which it will be noted that the rear side portions of the sheet have been bent inward on the imaginary lines $c-c$. Next, the folds having the buttonholes a^2 are brought down and applied 65 on the buttons a , and finally, the folds having the buttonholes b^1 are brought down and applied to the buttons b , and this gives the completed form to the bonnet or cap. The brim 2 can be turned forward, as shown in 70 Fig. 2, or may be turned back as shown in Fig. 3.

The arrangement above described is the most desirable, but it is possible to apply all of the buttonholes a^1 , a^2 , and b^1 on the buttons a . 75

In actual practice, this improved bonnet or cap has been found to be thoroughly practicable, highly desirable, and commercially valuable. It may be made of all sorts of 80 different materials, as well as in various different ornamental or plain designs.

What I claim is:

1. A bonnet or cap formed from a substantially rectangular sheet having at front 85 and rear corners of each of its side edge portions a separable fastener for connecting said corners, and separable fasteners for holding the intermediate portion of each of its side edge portions gathered. 90

2. A bonnet or cap formed from a substantially rectangular sheet having at front and rear corners of each of its side edge portions a separable fastener for connecting said corners, the intermediate portion of the sheet 95 at each of its side edge portions being gathered, and separable fasteners for holding gathered portions of said sheet to the front edge portion thereof.

3. A bonnet or cap formed from a substantially rectangular sheet having at front and rear corners of each of its side edge portions a separable fastener for connecting said corners, the intermediate portion of the sheet at each of its side edge portions being gathered, and secured in part by the separable fasteners at the front corners of said sheet, and other separable fasteners securing the gathered portions of said sheet in part to the front edge portion of said sheet. 100 105 110

4. A bonnet or cap formed from a substantially rectangular sheet having buttons

at its front corners and buttonholes at its rear corners and also having intermediate buttons at its front edge portion and an intermediate buttonhole between the corner button and buttonhole on each of its sides, said corner buttonholes being arranged for application to the corner buttons and the intermediate buttonholes being arranged for application to the intermediate buttons.

10 5. A bonnet or cap formed from a rectangular sheet having buttons at its front corners and buttonholes at its rear corners, and also having two intermediate buttons at

its front edge portion and two intermediate buttonholes at each of its side edge portions, 15 said corner buttonholes and the rear intermediate buttonholes being arranged for application to the corner buttons and the front intermediate buttonholes being arranged for application to the intermediate buttons, adapting the sides to be gathered in folds 20 and secured to give form to the bonnet or cap.

In testimony whereof I affix my signature.

ELsie LARSON.
